US0D1030409S

(12) **United States Design Patent** (10) **Patent No.:** **US D1,030,409 S**
(45) **Date of Patent:** **** Jun. 11, 2024**

(54) **STEAMER**

(71) Applicant: **The Cookware Company Global Sourcing Limited**, Kowloon Bay (HK)

(72) Inventor: **Jan Hoekstra**, Ghent (BE)

(73) Assignee: **THE COOKWARE COMPANY GLOBAL SOURCING LIMITED**, Kowloon Bay (HK)

(**) Term: **15 Years**

(21) Appl. No.: **29/814,878**

(22) Filed: **Nov. 9, 2021**

(30) **Foreign Application Priority Data**

May 10, 2021 (EM) 008535348-0001

(51) **LOC (14) Cl.** **07-02**

(57) **CLAIM**

The ornamental design for a steamer, as shown and described.

DESCRIPTION

FIG. 1 is a top perspective view of a steamer, showing my new design;

FIG. 2 is a front view thereof;

FIG. 3 is a perspective side view thereof;

FIG. 4 is a side view thereof;

FIG. 5 is a top plan view thereof; and,

FIG. 6 is a bottom plan view thereof.

The broken lines and the area encompassed by them in FIG. 6 depict portions of the steamer that form no part of the claimed design.

1 Claim, 6 Drawing Sheets
